UNITED STATES PATENT OFFICE.

JOHN D. WILLIAMS, OF WHITTENBURG, TEXAS.

OIL DERRICK.

Application filed September 21, 1926. Serial No. 136,853.

This invention relates to derricks such as are used in the oil fields for drilling wells and for like operations, and the general object of the invention is to provide means whereby the four legs or timbers of the derrick may be held rigidly together by the girts and corner angles and when the braces are tightened.

A further object is to provide inside and outside corner angle irons adapted to embrace the sections of the corner timbers when the angle irons are in place and provide girts engaged with said angle irons, the parts being so constructed that as the braces are tightened, the girts will also be tightened.

A still further object is to provide a derrick of this character which may be readily set up or readily taken down.

My invention is illustrated in the accompanying drawings wherein:

Figure 1 is a side elevation of the upper portion of an oil derrick constructed in accordance with my invention;

Fig. 2 is a cross section on the line 2—2 of Figure 1;

Fig. 3 is a perspective view of the upper end of one of the timbers;

Fig. 4 is a perspective view of one of the angle irons;

Fig. 5 is a perspective view of the upper angle iron;

Fig. 6 is a perspective view of a girt.

Referring to these drawings 10 designates the legs or corner timbers of the derrick which extend upward and inward toward the crown of the derrick and which may be made of wood, though other material may be used. These legs are formed of a plurality of sections, the sections abutting against each other and the upper end of each section is formed with a diagonally disposed groove 11 adapted to receive a diagonal bolt.

Coacting with the sections of the derrick legs are the outer angle irons 12 and the inner angle irons 13. The outer angle irons engage against the outer faces of the rectangular sections 10 and extend beyond these sections as illustrated, while the inner angle irons engage against the inner faces and the flanges of each angle iron are less in width than the width of the corresponding faces of the derrick sections.

The angle irons 12 and 13 are formed with apertures 14 for the passage of the bolt 15, this bolt being disposed within the groove

11 in the upper end of the derrick section 10. Each flange 16 of the angle iron 12 is provided at its upper and lower corners with the apertures 17 for engagement with the brace rods 18 and also with an aperture 19 for engagement with the bolt 20 which passes through a girt 21. The girt 21 is formed of an angle iron to provide a downwardly depending flange and a horizontally depending flange and it will be noted from Figure 6 that the vertical flange is extended beyond the horizontal flange as at 22 so that this extension of the vertical flange is disposed between the angle iron 12 and the two abutting sections 10 of the derrick leg, as illustrated in Figure 2.

The vertical flange of each girt 21 is formed with a longitudinally elongated aperture or slot 23 through which the bolt 20 passes so as to permit the girt to shift longitudinally with relation to this bolt 20 and with relation to the legs of the derrick. The braces 18 extend from the corner of one angle iron 12 to the corner of the other angle iron 12 diagonally opposite either up or down and each brace is provided in its length with a turnbuckle 24 whereby the brace may be tightened.

It will be seen now that as the cross braces 18 are tightened, the angle irons 12 will be shifted towards each other a certain amount, thus drawing the legs of the derrick towards each other and that the slots 23 will permit this movement of the legs of the derrick and of the angle irons 12 without affecting the girts 21. When the braces have been fully tightened, however, the girts will bear against the angular wall of the angle irons 12 and no further inward movement of the legs of the derrick is possible but the tightening up of the turnbuckles 24 will cause the various sections of the derrick to be held in rigid engagement with each other. The angle irons 12 and 13 at the upper end of the derrick legs are of the same form as the angle irons lower down except that there are two diagonally disposed bolts 15 extending through the upper ends of the uppermost leg sections instead of one bolt and obviously these diagonal bolts extend through diagonal apertures or passages formed in the upper ends of the uppermost leg sections.

The crown block 25 is disposed upon the upper ends of the uppermost leg sections and fits within the angular corner irons 12 in the manner illustrated in Figure 1 and may

be bolted thereto or otherwise engaged therewith.

The bolts 20 are preferably provided with resilient washers which will elastically bear 5 against the nuts and hold the nuts from any tendency to work off. While I have heretofore referred to the angle irons 12 and 13 as being of iron it will be understood that these will be made of steel or they may be made of 10 any suitable material.

It will be seen that by my system of construction derricks may be constructed of any height by using a series of leg sections, splicing these sections to each other by means 15 of the angle corner irons 12 and 13, placing the leg sections from each other by the girts which also act, of course, to prevent any spreading of the leg sections and drawing the angle irons towards each other and thus 20 drawing the sections into rigid engagement with the girts by means of the cross brace rods with their turnbuckles. A derrick constructed in accordance with this invention is much cheaper than the ordinary derrick, 25 may be more expeditiously handled and transported, and may be quickly put up or taken down. It will be seen that the angle iron corner pieces being attached as they are to the lower section and projecting above 30 this lower section, constitute sockets into which an upper section of a leg may be in-

serted and that each upper section is held in firm engagement with a lower section by the downward strain of the crossed braces. Obviously certain minor changes may be made 35 in the details of construction and arrangement of parts without departing from the spirit of the invention as defined in the appended claim.

I claim:

A derrick structure comprising aligned beam sections abutting at their ends and provided at their end edges with diagonally disposed registering recesses, angle plates applied to the outer surfaces of the abutting ends of the beam sections and having edge portions projecting beyond the inner surfaces of the beam sections, angle plates applied to the inner surfaces of the abutting end portions of the beam sections and having edges spaced from the projecting edge portions of the first mentioned angle plate, bolts lying in said recesses and passing through said plates and disposed transversely of the beam sections, and girt bars secured to the projecting end portions of the first mentioned plates and having end extremities clamped by the bolts against the side surfaces of the beam sections.

In testimony whereof I hereunto affix my signature.

JOHN D. WILLIAMS.
